COOKER FOR FRANKFURTERS OR THE LIKE

Melvin H. Boldt, Glenview, Ill., assignor to National Presto Industries, Inc., Eau Claire, Wis., a corporation of Wisconsin

Filed Dec. 4, 1959, Ser. No. 58,556

Term of patent 14 years

(Cl. D81—10)

FIG. 1

FIG. 2

FIGURE 1 is a perspective view of a cooker for frankfurters or the like showing my new design;

The dominant features of the design reside in the portions shown in full lines.

I claim:

The ornamental design for a cooker for frankfurters or the like, substantially as shown and described.
